UNITED STATES PATENT OFFICE.

GEORGE E. MOLYNEUX, OF BAYONNE, NEW JERSEY.

STOPPING MECHANISM FOR SEWING-MACHINES.

1,373,755.

Specification of Letters Patent.

Patented Apr. 5, 1921.

Application filed December 2, 1916. Serial No. 134,567.

To all whom it may concern:

Be it known that I, GEORGE E. MOLYNEUX, a citizen of the United States, and residing in the city of Bayonne, county of Hudson, 5 in the State of New Jersey, have invented certain new and useful Improvements in Stopping Mechanisms for Sewing-Machines, of which the following is a specification, reference being had to the accompanying 10 drawings, forming a part hereof.

The object of this invention is to provide improved devices for arresting quickly, without shock or jar, and with the parts in predetermined position, the movement of 15 high speed machines, such as power-driven sewing machines. Some devices intended for similar use are dependent, in some manner, upon centrifugal action, the structure including a movable part which is held in 20 normal or inoperative position by centrifugal action when the machine is operated at normal high speed and moves, when the speed falls below the normal, upon the opening of the transmission clutch, for example, 25 and by its movement initiates or permits the operation of the stopping devices. In the stopping mechanism which forms the subject of the present invention there is no part 30 which is held in normal position by centrifugal action and moves, when the speed is reduced, to initiate or permit the action of the stopping devices, but the construction is such that the act of opening the transmission clutch through which the machine is driven, 35 itself initiates the operation of the stopping devices, which are themselves preferably so arranged and constructed that a braking action is first exerted upon the moving parts of the machine and is then immediately released, so that if the machine is not stopped 40 by the braking action with its parts in predetermined positions, the movement of the machine, although retarded by the temporary braking action, may be continued there- 45 after until it is arrested, with the parts in predetermined positions, by positively acting stopping devices, which are suitably cushioned to prevent shock.

The invention will be more fully explained 50 hereinafter with reference to the accompanying drawings in which it is illustrated and in which,—

Figure 1 is a view in front elevation showing the improved stopping mechanism applied to the arm or frame of a sewing 55 machine.

Fig. 2 is a view in section on the plane indicated by the broken line 2—2 of Fig. 1, looking in the direction of the arrows.

Fig. 3 is a view in longitudinal section of 60 the parts shown in Fig. 1.

Fig. 4 is a view in section on the plane indicated by the broken line 4—4 of Fig. 3, looking in the direction of the arrows.

Fig. 5 is a top view of the parts shown 65 in Figs. 1 and 3.

Fig. 6 is a view in section on the plane indicated by the broken line 6—6 of Fig. 3, looking in the direction of the arrows.

Fig. 7 is a detail view in perspective of 70 the carrier slide-block.

The improved mechanism is shown in the drawings as adapted for application to an ordinary, straightaway sewing machine, the bedplate of which is indicated at *a*, the usual 75 arm or frame at *b*, the driving shaft at *c* and the driving pulley at *d*.

A relatively fixed member *e*, preferably a plate or disk, is shown as mounted fixedly on a hub *b'* of the arm or frame *b*, this 80 member serving as a support and guide for the carrier slide-block hereinafter referred to and also furnishing a support for the bell-crank hereinafter mentioned.

On the right hand face of the member *e* 85 is secured, as by a screw *f'*, at its middle part, a split brake-band or ring *f*, which is normally truly circular and has its free ends separated by a narrow gap *f*². In a radial groove *e'*, formed in the right hand face of 90 the member *e* and provided at its lower end with a keep *e*², is supported and guided a carrier guide-block *g* which is provided with a stop-lug *g'*, a brake-actuating pin *g*², adapted to enter the gap between the ends 95 of the brake-ring *f* for the purpose of spreading the brake-ring and also to pass entirely through the gap so as to release the brake, and an actuating pin *g*³, by which the slide-block is moved radially toward the axis 100 of the shaft *c* for the purpose of causing the pin *g*² to actuate and release the brake. A spring *g*⁴ acts upon the slide-block to supplement the weight thereof and press it normally away from the shaft *c*.

Also mounted on the hub *b'*, but loosely, so that it may rotate thereon and also move laterally thereon toward and from the member *e*, is a disklike member *h* which, in the construction shown, has a triple function. It serves as a brake member to coöperate 110 with the split brake-ring *f*, as a slide-block

actuator to actuate the slide-block g and as a positive stop. In its left hand face it is provided with an angular, truly circular groove h' which is adapted to receive the 5 brake-ring f when the member h is moved toward the member e , receiving the brake-ring with a free fit but with little clearance. It is also provided, in its left hand face, with a spiral groove h^2 for coöperation with 10 the pin g^2 of the slide-block, to move the slide-block inwardly. This spiral groove is shown in Fig. 2 as having nearly two complete turns, but its length will be varied according to the character and especially ac- 15 cording to the speed of the machine to which the stopping mechanism is applied. It is also provided, on its perimeter with a positive stop-lug h^3 for coöperation with the stop-lug g' on the slide-block g , which is 20 carried by the relatively stationary member e . It has also on its right hand face a stop-lug h^4 to coöperate with a stop-lug of the shock absorber to be referred to. A spiral spring h^5 , surrounding the hub b' , acts nor- 25 mally upon the member h to press it away from the member e and therefore to keep it out of contact with the brake-ring, the movement of the member h to the right being limited by pins h^6 .

30 The driving pulley d is fixed upon the driving shaft c , as by a set-screw d' , and has a long hub d^2 , which extends to the left toward the hub b' . Keyed on the hub d^2 , so as to be free to slide longitudinally thereon 35 but to rotate therewith, is a shock absorbing member h , which is provided, in the usual manner, with a stop-lug h' to coöperate with the stop-lug h^4 , above mentioned, this stop-lug h' being movable to a limited extent with 40 respect to the shock absorber h and held between two springs h^2 and h^3 , which cushion the parts respectively against the shock of stopping and the shock of the rebound. The hub of the shock absorber is grooved circum- 45 ferentially as at h^4 , and is engaged by the forked end l' of the bell crank l which is pivoted at l^2 on the above mentioned arm b^2 . The other arm l^3 of the bell crank is connected by a link l^4 to the usual foot-operated 50 devices for controlling the clutch of the transmission through which the machine is driven. The spring l^5 is applied to the link l^4 to press it upwardly. In the operation of high speed sewing machines the 55 pressure of the operator's foot on the pedal throws in the clutch of the transmission and pulls down the link l^4 against the spring l^5 so as to hold the member h in its right hand position. When it is desired to stop the 60 machine, the pressure of the operator's foot on the pedal is removed, the clutch of the transmission is thereupon opened, and the action of the spring l^5 on the link l^4 , through the bell crank l , causes the member h to be 65 moved toward the left. The lug h' (which

is made sufficiently long for this purpose) presses against the right hand face of the member h and causes it to move toward the left against the pressure of the spring h^5 . This movement of the member h causes the 70 circular groove h' , in its left hand face, to receive the brake-ring f and at the same time causes the spiral groove h^2 to engage the pin g^2 of the slide block. As the lug h' also engages the lug h^4 of the member h , the latter is then made to rotate with the driving pulley d and the shaft c , so that the spiral groove h^2 then causes the slide-block 75 g to be moved inwardly toward the shaft c and the pin g^2 to be moved into the gap 80 between the ends of the brake-ring, thereby expanding the brake-ring within the groove h' and either stopping the rotation of the member h and, through the shock absorber, the rotation of the shaft c , while 85 the pin g^2 is in the gap, thereby arresting the movement of the machine with its parts in predetermined positions, or, if the momentum of the machine is too great to permit the stopping of the machine by the ac- 90 tion of the brake only, the continued rotation of the member h causes the pin g^2 to move through the gap, thereby immediately releasing the brake and permitting the rotation of the parts to continue until the lug 95 h^3 makes contact with the lug g' , whereupon the movement of the machine will be arrested positively, the shock being cushioned through the shock absorber as already understood.

100 The clearance between the brake-band and the outer wall of the groove h' in the member h is so slight that a very slight increase of the distance between the ends of the brake-band is sufficient to cause the predetermined braking effect to be produced and the elasticity of the brake-band is such that the brake-band itself offers but little resistance to the separation of its ends by the pin g^2 .

105 In restarting the machine the pressure of the operator's foot is applied to the clutch-pedal and the clutch is closed. At the same time the link l^4 is pulled down and, through the bell crank l , the shock absorber h is 110 moved to the right. This movement withdraws the lug h' from the right hand face of the member h which is then moved to the right by the spring h^5 , leaving the brake-band free. The elasticity of the brake-band 115 is such, as already stated, that the ends separate readily and the pin g^2 , if it stood between the ends when the machine stopped, is immediately released, and moves to its lowest position, clear of the brake-band, or, if the machine was not stopped by the application of the brake but continued to operate until the lug h^3 contacts with the lug g' , with the pin g^2 within the circle of the brake-band f , the slide-block drops or is pressed by 120 125 130

the spring g^4 to its lowest position, the pin g^2 passing readily through the gap between the ends of the free brake-band.

While the pressure of the operator's foot 5 remains on the clutch-pedal the shock absorber is held so far to the right that the lug h' clears the lug h^4 and the member h therefore does not rotate, but as soon as the pressure of the operator's foot is removed 10 the member h moves to the left and the lug h' , if it first contacts with the face of the lug h^4 , immediately moves beyond it, in the direction of its rotary movement, and then bears against the face of the member h to 15 cause its movement to the left as already described.

If the speed of the machine is not too high and the momentum of the moving parts is not too great the machine may be brought 20 to rest by the application of the brake alone, but if the speed is higher and the momentum greater, the energy will be absorbed largely by the brake and the movement of the parts will then be arrested positively by the contact of the block h^3 with the relatively stationary block g' , the reaction being transmitted through the lugs h^4 and h' to the shock absorber and thence to the driving shaft c .

30 It will be understood that the end of the spiral slot h^2 is continued to such a point as to leave a clearance between the pin g^3 and the end of the slot when the lug h^3 makes contact with the lug g' and the pin g^3 therefore is not subjected to the shock of stopping.

Various changes in details of construction and arrangement may be made to suit different conditions of use and the invention 40 is not limited to the precise construction shown and described herein.

I claim as my invention:

1. In a stopping mechanism, the combination of a relatively stationary member, a rotatable member, a brake-ring carried by one of said members, the other of said members being formed with a coöperating brake-surface, said members being held normally with the brake-ring and the coöperating brake-surface in inoperative relation, means to move one of said members to place the brake-ring and brake-surface in operative relation, and means to actuate the brake-ring to exert a braking action on the brake-surface.

2. In a stopping mechanism, the combination of a relatively stationary member, a rotatable member, a split brake ring carried by one of said members, the other of said members being formed with a coöperating brake surface, a pin adapted to pass between the ends of the brake ring to spread the same and means to move said pin into position between the ends of the brake ring 65 to spread the same and to continue the move-

ment of the pin beyond the ends of the brake ring to release the brake.

3. In a stopping mechanism, the combination of a relatively stationary member, a rotatable member, a split brake-ring carried by one of said members, the other of said members being formed with a coöperating brake-surface, a slide-block radially movable with respect to the brake-ring, a pin carried by said slide-block and adapted to pass between the ends of the brake-ring to spread the same, and means to move the slide-block.

4. In a stopping mechanism, the combination of a relatively stationary member, a split brake-ring carried by said stationary member, a rotatable member mounted coaxially with the brake-ring and grooved to form a brake-surface to coöperate with the brake-ring, and having also a spiral groove, and a slide-block radially movable on the stationary member and having a pin to engage the spiral groove of the rotatable member and another pin to enter the gap between the ends of the brake-ring and spread the same.

5. In a stopping mechanism, the combination of a brake, a coöperating brake surface, a single operating means to apply the brake and in its continued movement to release the same immediately, and positive stopping devices acting after the release of the brake to stop the continued movement of the moving parts.

6. In a stopping mechanism, the combination of a relatively stationary member, a rotatable member, a brake carried by one of said members, the other of said members being formed with a coöperating brake-surface, means to apply the brake and to release the same immediately, and coöperating stop-lugs carried by said members respectively to stop positively the rotation of the rotatable member after the release of the brake.

7. In a stopping mechanism, the combination of a relatively stationary member, a rotatable member, a brake carried by one of said members, the other of said members being formed with a coöperating brake surface, means to apply the brake and to release the same immediately, a stop-lug carried by one of said members, a radially movable stop-lug carried by the other of said members, and means to move the last-named lug into operative relation with the first.

8. In a stopping mechanism, the combination of a relatively stationary member, a rotatable member having a spiral groove and having a stop-lug, and a slide-block mounted in a radial groove of the stationary member to move radially thereon and independently thereof and having a pin to engage the spiral groove, and a stop-lug to be moved thereby into the path of the lug on the rotatable member.

9. In a stopping mechanism, the combination of a relatively stationary member, a split brake-ring carried thereby, a rotatable member formed with an annular coöperating brake-surface and with a spiral groove, and having a stop-lug, and a slide-block radially movable on the stationary member and having a pin to engage the spiral groove of the rotatable member whereby the block 10 is moved radially, a pin to pass through the gap between the ends of the split ring and spread the same, and a stop-lug movable with the block into the path of the stop-lug on the rotatable member.
15. 10. In a stopping mechanism, the combination of a relatively stationary member, a rotatable member movable toward and from the stationary member, a brake-ring carried by one of said members and the 20 other member being formed with a coöperating brake-surface, means to cause the brake to exert a braking action on the brake-surface, a driving shaft mounted coaxially with the rotatable member, a sleeve member mounted to rotate with the driving shaft and move longitudinally with respect thereto, a device carried by the sleeve member to bear 25 against and to move said rotatable member toward the stationary member, and means to shift the sleeve-like member longitudinally.
30. 11. In a stopping mechanism, the combination of a relatively stationary member, a rotatable member movable toward and from the stationary member, a brake-ring carried by one of said members and the other member being formed with a coöperating brake-surface, means to cause the brake to exert a braking action on the brake-surface, a driving shaft mounted coaxially with the 35 rotatable member, a sleeve member mounted to rotate with the driving shaft and move longitudinally with respect thereto to move said rotatable member toward the stationary member, means to shift the sleeve-like member longitudinally, the rotatable member and the sleeve-like member having coöperating stop-lugs, and the lug on the sleeve-like member being cushioned to absorb the shock.
12. In a stopping mechanism, the combination of a relatively stationary member, a rotatable member movable toward and from the stationary member, a brake-ring carried by one of said members and the other member being formed with a coöperating brake-surface, means to cause the brake to exert a braking action on the brake-surface, a driving shaft mounted coaxially with the rotatable member, a sleeve member mounted to rotate with the driving shaft and move longitudinally with respect thereto to move said rotatable member toward the stationary member, means to shift the sleeve-like member longitudinally, the rotatable member and the sleeve-like member having coöperating stop-lugs, and the lug on the sleeve-like member being cushioned to absorb the shock.
13. In a stopping mechanism, the combination of a rotatable member, means adapted to coöperate with the rotatable member to stop the movement thereof, a driving shaft mounted coaxially with the rotatable member, a sleeve-like member mounted to rotate with the driving shaft and movable toward and from the rotatable member, the sleeve-like member and the rotatable member having coöperating lugs, and means to shift the sleeve-like member.
14. In a stopping mechanism, the combination of a rotatable member, means adapted to coöperate with the rotatable member to stop the movement thereof, a driving shaft mounted coaxially with the rotatable member, a sleeve-like member mounted to rotate with the driving shaft and movable toward and from the rotatable member, the sleeve-like member and the rotatable member having coöperating lugs, and means to shift the sleeve-like member, the sleeve-like member being provided with shock absorbing devices.

This specification signed this 29th day of November, A. D. 1916.

GEORGE E. MOLYNEUX.
